ROLLER BIT

Alfred C. Catland, Alhambra, Calif., assignor to
 Globe Oil Tools Company, Los Nietos, Calif.,
 a corporation of California

Application May 25, 1935, Serial No. 23,395

14 Claims. (Cl. 255—71)

This invention relates to a well drilling tool and has particular reference to a roller bit for use in the rotary method of well drilling. A general object of this invention is to provide an improved roller bit that is inexpensive and that is very rapid and efficient in operation.

Another object of the invention is to provide a roller bit embodying three circumferentially spaced roller cutters for cutting the well bore to gauge and for drilling the outer portion of the well bore and a pair of inner cutters for drilling the inner portion of the bore, the inner and outer roller cutters being related to provide for the steady efficient operation of the bit.

Another object of this invention is to provide a roller bit of the character mentioned embodying a novel and dependable means for mounting and retaining the several rotatable roller cutters.

Another object of the invention is to provide a roller bit for well drilling in which all of the wearing parts may be easily and quickly replaced at the well or in the field after each run, if necessary, by simple, common tools.

Another object of the invention is to provide a roller bit embodying a single simple cutter support or member that provides a spindle for carrying the inner cutters, that retains the outer cutters on their shafts or spindles, that protects the inner sides of the outer cutters and the bearings and bushings of the outer cutters, and that directs the discharging circulation fluid against the bottom of the well bore and against the cutters.

Another object of the invention is to provide a roller bit in which the circulation fluid is discharged downwardly in a wide stream from a point adjacent the bottom of the well bore to have an effective hydraulic action in eroding the formation throughout a wide path at the bottom of the bore.

The various objects and features of the invention will be fully understood from the following detailed description of a typical form and application of the invention, throughout which description reference is made to the accompanying drawings, in which:

Fig. 1 is a side elevation of the bit provided by the present invention. Fig. 2 is an enlarged bottom elevation of the bit. Fig. 3 is an enlarged fragmentary vertical detailed sectional view taken substantially as indicated by line 3—3 on Fig. 1. Fig. 4 is an enlarged fragmentary vertical detailed sectional view taken substantially as indicated by line 4—4 on Fig. 2. Fig. 5 is a bottom elevation view showing the outer

cutters and their bearings in position with the cutter mounting and retaining member and the inner cutters removed. Fig. 6 is a side elevation of the cutter mounting and retaining member apart from the bit and Fig. 7 is a top or plan view of the said member.

The improved roller bit provided by my invention includes, generally, a shank 10, spaced outer cutters A, B and C carried by the shank 10, a removable member 11 attached to the shank 10, and inner cutters D carried by the member 11.

The body or shank 10 of the bit is adapted to be connected to the lower end of a well drilling string and is provided and formed to carry the cutters A, B and C and the member 11. The major portion 12 of the shank 10 is cylindrical and is provided at its upper end with means for connecting with the drilling string. In the particular case illustrated in the drawings a screw threaded pin 13 is provided on the upper end of the shank 10 for facilitating its connection with a drill collar or other part of a drilling string. In accordance with the invention downwardly projecting wings or legs 14 are provided on the lower end of the shank 10 for carrying the cutters A and B and a similar leg 15 projects from the lower end of the shank to carry the cutter C. The legs 14 and 15 project outwardly and downwardly from the lower end portion of the shank 10 and the outer surfaces of the legs are preferably curved to be substantially concentric with the longitudinal axis of the bit. The legs just described are preferably equally spaced one from the other. The lower face or end 16 of the shank 10 is preferably flat and normal to the vertical axis of the shank. The inner side 17 of the legs 14 and 15 are inclined downwardly and outwardly with respect to the vertical axis of the bit. Shafts or spindles 18 are provided on the legs 14 to carry the cutters A and B and a similar spindle 19 is provided on the leg 15 to support the cutter C. The spindles 18 and 19 are preferably integral with their respective legs and project downwardly and inwardly from the inner sides 17 of the legs. The longitudinal axis of the spindles 18 and 19 are preferably normal to the inner sides 17 of the legs.

The cutters A, B and C are rotatable on their respective spindles to cut the well bore to gauge and to drill or form the outer portion of the well bore. The outer cutters A, B and C are in the nature of substantially cylindrical roller cutters provided with peripheral cutting parts or teeth 20. The cutters A and B are compara-

tively narrow while the cutter C is wider to have more extensive engagement with the formation at the bottom of the well bore. The opposite ends of the cutters A, B and C may be flat and 5 normal to the axis of the cutters as illustrated in the drawings. The cutting teeth 20 may be straight and axial and the opposite ends of the teeth 20 of the cutters A, and B may be bevelled away or inclined. The outer ends of the cutting 10 teeth 20 of the large outer cutter C are preferably bevelled to properly engage the formation at the side wall of the well bore while the inner ends of the teeth 20 of this cutter may be straight and may extend to the inner end of the 15 cutter. The cutters A, B and C being rotatable on the spindles 18 and 19 rotate about downwardly and inwardly inclined axes and project downwardly and outwardly beyond the lower 20 ends of the legs 14 and 15 to act on the formation at the side wall and bottom wall of the bore.

Wear taking bushings 21 are provided on the 25 spindles 18 and roller bearings 22 are provided for mounting or carrying the cutters A and B for free rotation on the bushings 21. The bushings 21 are readily replaceable when worn and are provided at their outer ends with radial flanges 23, for bearing on the inner sides 17 of the legs 14. Dowel pins 24 cooperate with notches in the flanges 23 to hold the bushings 21 30 against rotation. A replaceable wear taking bushing 25 is provided on the spindle 19 and the cutter C is rotatable on the bushing through a roller bearing 26. The bushing 25 has a radial flange 27 on its outer end for bearing against 35 the inner side 17 of the leg 15. A dowel pin 28 cooperates with a notch in the flange 27 to hold the bushing 25 against rotation. As will be hereinafter described the member 11 receives the 40 inward thrusts from the cutters A, B and C and the bearings 22 and 26 and prevent the displacement of the cutters and their mounting bearings and bushings from the spindles. The cutters A, B and C mounted as just described have active engagement with the earth formation to maintain the well bore to gauge. The 45 large outer cutter C has substantial engagement with the formation at the bottom of the well bore to make an annular cut as well as aiding in cutting the bore to gauge. The cutters A, B and C in being circumferentially spaced effectively steady and guide the bit.

The member 11 is provided to carry the inner cutters D and to retain the cutters A, B and C on their respective spindles. The member 11 also 50 forms a discharge nozzle or device for discharging the circulation fluid. The member 11 is a simple one piece element that can be easily detached from the shank 10 to allow the easy removal of the several cutters and their 55 mountings. The member 11 has flanges 30 at its upper end for bearing upwardly against the lower face 16 of the shank 10. In the construction illustrated there are three flanges 30 projecting radially outwardly between the three spaced legs 14 and 15. Openings or slots 31 are provided in 60 the outer ends of the flanges 30 to receive studs 32 which project from the lower end of the shank. Nuts 33 are threaded on the studs 32 to clamp the flanges 30 against the lower end 16 of the shank and thus attach the member 11 to the shank. Cotter keys 34 may be provided to lock the nuts 33 against displacement.

The member 11 projects downwardly within 65 the series of legs 14 and 15 and is provided with laterally projecting parts 35 and 36. The part

35 has a downwardly and outwardly inclined outer surface 38 adapted to bear on the end of the bushing 21 carrying the cutter A. The part 35 is sufficiently large to shield and protect the inner side of the cutter A and its bearing 22 and bushing 21. The part 35 thus retains the cutter A and its bushing 21 and bearings 22 on the spindle 18 and forms an abutment which receives inward end thrusts from the cutter. The part 36 of the member 11 has a downwardly and 10 outwardly inclined outer face 39 which bears on or engages the inner end of the bushing 21. The part 36 shields and protects the inner side of the large outer cutter C and retains the cutter and its bushing 25 and bearings 26 on the spindle. 15 The surface 39 of the part 36 is adapted to receive inward thrusts from the cutter C and the bearings 26.

The spindle 18 carrying the cutter A has a central longitudinal opening 40 extending to the 20 outer surface of the leg 14. An opening 41 is provided in the part 35 to communicate with the opening 40. A screw 42 extends through the opening 40 and is threaded into the opening 41 to connect the part 35 with the spindle 18. 25 The head of the screw 42 is received in a counterbore in the outer end of the opening 40. The spindle 19 has a central longitudinal opening 43 extending inwardly from the outer surface of the leg 15. An opening 44 is provided in the 30 part 36 to register with the opening 43. A screw 45 is arranged through the opening 43 and threaded in the opening 44 to connect the part 36 with the spindle 19. A counterbore at the outer end of the opening 43 receives the head of 35 the screw 45. Cotter pins may be provided to prevent unthreading of the screws 42 and 45. The screws 42 and 45 connect the leg 15 and one of the legs 14 with the member 11 to strengthen and lend rigidity to the construction. 40

The member 11 is provided with a spindle 46 for carrying the inner cutters D. In the preferred form of the invention the spindle 46 is disposed in the same radial or vertical plane as the spindle 18 carrying the cutter B. The spindle 46 extends outwardly from adjacent the central vertical axis of the bit and its outer end may engage the inner end of the spindle 18 which supports the cutter B. The spindle 46 is inclined downwardly and inwardly but at a lesser 45 angle than the said spindle 18. The outer end of the spindle 46 may be received in a socket 47 in the inner end of the spindle 18. A central longitudinal opening 48 extends through the spindle 46 from the inner said of the member 11. An opening 49 is provided in the spindle 18 to register with the opening 48. A screw 50 extends through the opening 48 and is threaded in the opening 49 to tie together the spindle 46 and the spindle 18 carrying the cutter B. 55

The inner cutters D are provided to act on and cut away the formation at the bottom of the bore within the path or cut made by the large outer cutter C. In accordance with the invention the inner cutters D have active engagement 60 with the formation from a point adjacent the central vertical axis of the bit to the inner margin of the cut made by the large outer cutter C. The cutters D are rotatable on the spindle 46 to turn about a downwardly and inwardly 65 inclined axis in the same radial plane as the cutter B. The cutters D are in the nature of substantially frusto-conical roller cutters. Peripheral cutting parts or teeth 51 are provided on the cutters D. The teeth 51 may be straight 70

and axial, as illustrated. In the particular embodiment of the invention shown in the drawings there are two inner cutters D arranged in end to end relation. The outermost inner cutter D has the largest diameter and the two cutters D are related so that their teeth 51 are adapted to act in a common substantially horizontal plane at the bottom of the well bore. A replaceable wear taking bushing 52 is provided on the spindle 46 and is provided at its outer end with a flange 53 to form a thrust washer or member for the cutters D and to shield the cutter B. The flange 53 has a downwardly and outwardly inclined outer surface for engaging the bushing 21. A pin 54 holds the removable bushing 52 against rotation on the spindle 46. A thrust washer 55 may be provided on the spindle 46 at the inner end of the bushing 52. The flange 53 is adapted to receive the outward end thrusts from the cutters D. Roller bearings 56 may be provided to support the cutters D for free rotation on the bushing 52.

The invention provides novel means for handling the rotary mud or circulation fluid. A central longitudinal fluid passage 57 is provided in the shank 10 to conduct the fluid downwardly from the drilling string. The passage 57 terminates at its lower end in a reduced opening 58. A replaceable bean or nipple 59 is threaded in a socket in the lower end of the opening 58 and projects downwardly beyond the lower end 16 of the shank. A socket 60 in the upper end of the member 11 receives the projecting portion of the nipple 59. In accordance with the invention the member 11 has a main port 61 extending downwardly from the opening 62 of the nipple 59. The main port 61 extends to the lower end of the member 11 and discharges at a point adjacent the inner end of the spindle 46 and thus conducts the circulation fluid to a point near the bottom of the well bore. The discharge end of the main port 61 is transversely elongated to discharge a wide stream of fluid which effectively flushes across the bottom of the well bore to have an eroding action and to maintain an effective turbulence in the lower end of the bore. The greater proportion of the circulation fluid discharges from the lower end of the main port 61 at a comparatively high velocity and has a powerful hydraulic action in eroding and cutting away the formation at the bottom of the bore to increase the cutting or drilling speed of the bit.

Means is provided for flushing the several cutters. The member 11 has a reduced port 63 communicating with the opening 62 of the nipple 59 and discharging downwardly above the inner cutters D. The fluid discharged from the port 63 washes the inner cutters D and the adjacent outer cutter B. A reduced port 64 in the member 11 conducts fluid downwardly from the opening 62 and directs it against the large outer cutter C to flush it free of accumulations or cuttings, etc. A similar port 65 is provided in the member 11 to discharge a stream of circulation fluid downwardly and outwardly against the outer cutter A. The reduced ports 63, 64 and 65 thus provide for the individual washing or flushing of the several cutters while the main port 61 conducts the major portion of the circulation fluid to a point adjacent the bottom of the well bore to assist in the drilling by eroding or washing away the formation.

In operation the bit is connected with the lower end of a drilling string and is rotated and

fed downwardly in the usual manner. The spaced outer cutters A, B and C act on the formation to cut the bore to gauge and make an annular cut forming the outer portion of the bore. The large outer cutter C being of considerable width acts on a comparatively wide inclined annular shoulder of the formation. The three spaced outer cutters A, B and C in engaging the formation at circumferentially spaced points steady and guide the bit. The outer roller cutters A, B and C in being inclined downwardly and outwardly are particularly rapid and efficient in their cutting engagement with the earth formation. The inner cutters D are offset from the central vertical axis of the bit to follow a circular or annular path to make an annular cut in the formation. The annular cut made by the inner cutters D extends outwardly from adjacent the center of the bore to the inner edge of the cut made by the large outer cutter C. Thus the entire bottom wall or substantially the entire bottom wall of the bore is actively engaged by the cutters of the bit. As described above, the circulation fluid discharging under pressure from the main port materially aids in the drilling action.

When the parts become worn after operation they may be easily and quickly removed for replacement. The member 11 is quickly detached from the shank 10 by removing the nuts 33 and 30 the screws 42, 45 and 50. These operations can be performed with common or typical wrenches. All the wearing parts of the bit are removable for replacement. The several cutters A, B, C and D and their bushings and bearings, are free for removal upon the detachment of the member 11 from the shank. Further, if necessary, the member 11 may be replaced or repaired. The member 11 in addition to carrying the inner cutters D protects the inner sides of the outer cutters A and C and forms a thrust member for receiving thrusts from these cutters and their bearings and bushings. The member 11 in being connected with the legs 14 and 15 by the screws 42, 45, and 50 is rigidly held in place and rigidly ties together the spaced parts or legs of the bit.

Having described only a typical preferred form and application of my invention, I do not wish to be limited or restricted to the specific details set forth, but wish to reserve to myself any variations or modifications that may appear to those skilled in the art or fall within the scope of the following claims.

Having described my invention, I claim:

1. A well bit including a shank having a plurality of integral bearings projecting therefrom, an outer roller cutter rotatably carried on each bearing to project below the shank, a member removably attached to the shank and positioned to retain said outer cutters on their bearings, and an inner roller cutter carried by said member to rotate in spaced relation to the outer cutter and act on the formation being drilled within the path of the outer cutter.

2. A well bit including a shank, three circumferentially spaced outer roller cutters rotatably supported by the shank with their outermost cutting portions equidistant from the central longitudinal axis of the bit to uniformly cut clearance for the bit, a removable member on the lower end of the shank, and an inner roller cutter carried by the member at a point inwardly from one of the outer cutters to rotate about an axis in substantially the same vertical plane

as the axis of said outer cutter to act on the formation within the path of the outer cutter.

3. A well bit including, a shank, outer roller cutters rotatably mounted on the shank to act on the formation at circumferentially spaced points to maintain the well bore to gauge, a member removably attached to the shank, a spindle on the member, a bushing on the spindle retaining one of the outer cutters in place, 10 and an inner roller cutter rotatable on the bushing.

4. A well bit including a shank, spaced legs projecting downwardly from the lower end of the shank, inwardly projecting spindles on the 15 legs, roller cutters rotatable on the spindles projecting uniformly radially of the shank to uniformly cut clearance for the bit, a member removably attached to the lower end of the shank and retaining the said cutters on the spindles, 20 and an inner roller cutter carried by the member to act on the formation within the path of the first mentioned cutters.

5. A well bit including a shank, spaced legs projecting downwardly from the lower end of the shank, inwardly projecting spindles on the 25 legs, roller cutters rotatable on the spindles and adapted to act on the formation to maintain the well bore to gauge, a member removably attached to the lower end of the shank, a spindle 30 on the member extending outwardly to engage one of the inwardly projecting spindles, and an inner roller cutter rotatable on the last mentioned spindle.

6. A well bit including a shank, spaced legs 35 projecting downwardly from the lower end of the shank, inwardly projecting spindles on the legs, roller cutters rotatable on the spindles projecting uniformly radially beyond the shank and adapted to act on the formation to cut 40 clearance for the bit, a member removably attached to the lower end of the shank and retaining the said cutters on the spindles, removable means connecting the spindles and member, and an inner roller cutter carried by the 45 member to act on the formation within the path of the first mentioned cutters.

7. A well bit including a shank, spaced legs projecting downwardly from the lower end of the shank, downwardly and inwardly inclined 50 spindles on the inner sides of the legs, roller cutters rotatable on the spindles so that their outermost cutting parts are equidistant from the central longitudinal axis of the bit and adapted to act on the formation to cut clearance 55 for the bit, a member removably attached to the lower end of the shank, a downwardly and inwardly inclined spindle on the member, and a roller cutter on the last mentioned spindle for acting on the formation at the bottom of the bore.

8. A well bit including a shank, spaced legs projecting downwardly from the lower end of the shank, inwardly projecting spindles on the 60 legs, removable bushings on the spindles, roller cutters rotatable on the bushings and operable 65 to engage the formation to uniformly drill clearance for the bit, a member detachably connected to the shank and retaining the bushings on the spindles and the cutters on the bushings, and 70 an inner roller cutter carried by the member.

9. A well bit including a shank, spaced legs projecting downwardly from the lower end of the shank, inwardly projecting spindles on the 75 legs, removable bushings on the spindles, roller cutters rotatable on the bushings and operable

to engage the formation to drill the bore to gauge, a member detachably connected to the shank and retaining the bushings on the spindles and the cutters on the bushings, screws connecting the spindles with the member, and 5 an inner roller cutter carried by the member.

10. A well bit including a shank, three circumferentially spaced legs projecting downwardly from the shank, spindles projecting inwardly from the legs, outer roller cutters 10 rotatable on the spindles adapted to drill the bore to gauge, a removable member projecting from the shank, parts on the member adapted to receive inward thrusts from two of the said cutters, a spindle on the member, a part on the last 15 mentioned spindle adapted to receive inward thrusts from the other outer cutter, and an inner roller cutter rotatably supported on the spindle of the member.

11. A well bit including a shank, three circumferentially spaced legs projecting downwardly from the shank, spindles projecting inwardly from the legs, outer roller cutters 20 rotatable on the spindles adapted to drill the bore to gauge, a removable member projecting from the shank, parts on the member adapted to receive inward thrusts from two of the said cutters, a spindle on the member, a bushing on the last mentioned spindle adapted to receive inward thrusts from the other outer cutter, and 25 an inner roller cutter rotatable on the bushing to engage the formation at the bottom of the well bore.

12. A well bit including, a shank, roller cutters rotatably carried by the shank to act on the 35 formation at circumferentially spaced points to maintain the well bore to gauge, a member removably attached to the shank, and an inner roller cutter carried by the member to act on the formation within the path of the outer cutters, there being a fluid passage in the shank and a fluid carrying port formed directly in the member to communicate with and receive fluid from the passage, the walls of said port acting 40 to confine the fluid and direct it downwardly 45 from a point adjacent the bottom of the well bore to erode the formation.

13. A well bit including a shank, three circumferentially spaced legs projecting downwardly from the shank, spindles projecting inwardly from the legs, outer roller cutters 50 rotatable on the spindles to drill the bore to gauge, a member disposed between the legs, a flange on the member bearing against the lower end of the shank, releasable means clamping the flange 55 against the shank, the member being adapted to receive the inward thrusts from the outer cutters, and an inner roller cutter carried by the member.

14. A well bit including a shank, three circumferentially spaced legs projecting downwardly from the shank, spindles projecting inwardly from the legs, outer roller cutters 60 rotatable on the spindles to drill the bore to gauge, a removable member projecting from the shank, 65 parts on the member adapted to receive inward thrusts from two of the said cutters, a spindle on the member, a bushing on the last mentioned spindle, a flange on the bushing adapted to receive inward thrusts from the other outer cutter, and 70 an inner roller cutter rotatable on the bushing, the said flange being adapted to receive outward thrusts from the inner cutter.
